UNITED STATES PATENT OFFICE

LUTHER E. GROAT, OF LOS ANGELES, CALIFORNIA, ASSIGNOR, BY MESNE ASSIGNMENTS, OF ONE-HALF TO HIMSELF AND ONE-HALF TO AGDA E. ZIEGLER, OF LOS ANGELES, CALIFORNIA.

ELEVATOR-DOOR-ACTUATING DEVICE

1,269,927.

Specification of Letters Patent. Patented June 18, 1918.

Application filed April 8, 1916. Serial No. 90,012.

To all whom it may concern:

Be it known that I, LUTHER E. GROAT, a citizen of the United States, residing at Los Angeles, in the county of Los Angeles and State of California, have invented a new and useful Elevator-Door-Actuating Device, of which the following is a specification.

My invention relates to elevators such as are used in ordinary types of building construction.

The principal object of my invention is to provide a device by which the doors of such an elevator can be opened and closed in a minimum of time, with a minimum of effort, and a maximum of certainty. To accomplish this result certain new structure has been devised which will be set forth in detail in the following specification.

20 In the accompanying drawings,

Figure 1 is an elevation of a portion of a building showing an elevator car in an intermediate position between two floors, a portion of the building and the car being broken away and shown in section to better illustrate the invention.

Fig. 2 is an elevation on an enlarged scale of the door actuating device, a portion thereof being shown in section.

30 Fig. 3 is a section on a plane represented by the line x^3-x^3 of Fig. 2, viewed in the direction of the arrows.

Fig. 4 is a section on an enlarged scale on the line x^4-x^4 of Fig. 2, viewed in the 35 direction of the arrows.

Fig. 5 is a section through an interlock switch.

40 Fig. 6 is a view of one form of solenoid brake which may be used in connection with the motor of the actuating device.

Fig. 7 is a diagram of connections.

Fig. 8 is a view on an enlarged scale of the door operating lever and latch therefor.

45 Fig. 9 is a view on a plane represented by the line x^9-x^9 of Fig. 8 viewed in the direction of the arrows.

In the embodiment of the invention shown in the drawings, an elevator car 11 may be actuated through cables 12; or through hy-

draulic mechanism not shown. In the embodiment illustrated, which shows an electric elevator, a main controller 13 is provided, this controller being mounted in the car 11, and having an operating handle 14 by which the elevator operator controls the movements of the car. A door controller 15 is mounted in a convenient location in the elevator so that it can be readily manipulated by the elevator operator. An interlock switch 16 is mounted on the top of the car, being adapted to engage an interlock cam 17 placed in a suitable location in the elevator shaft in which the car 11 runs. As ordinarily constructed the elevator car proper is without a door, a door 19 being provided at each floor. A door actuating lever 18 is provided for each of the doors 19, and a door actuating device 20 is secured to the elevator car, this actuating device 20 being controlled by the door controller 15. 70 The door lever 18 is pivoted at 21 on a pin fixed in the structure surrounding the elevator shaft, this lever extending down and having a slot formed in the lower end thereof of which engages a pin 22 fixed on a panel 23 of the door 19, this door consisting of two panels 23 and 24 so connected that the panel 23 slides inside the panel 24, and the two panels thereafter move together behind a fixed panel 25. This construction being 75 already well known in the elevator art, and need not be described more in detail.

Pivoted on a pin 26, carried on the door operating lever 18 is a latch bar 29, this latch bar extending over and having secured 80 therein a pin 30, this pin carrying a rubber roller 31 which extends out into the shaft of the car in such a position to be engaged by the door actuating device 20 as will herein-after be described. Sliding on a T-shaped track 32 is a runner 33, this runner having a slot 34 formed therein. A roller 35 turns freely on the pin 30 and slides in the slot 34. A latch 36 is pivoted on a pin 37 on the runner 33, this latch engaging a notch 85 38 cut in the track 32 and extending over the roller 35 in such a position as to be lifted thereby as this roller slides in the slot 34.

A spring 39, secured to the runner 33, extends over and tends to force the latch 36 into the notch 38.

The rubber roller 31 is so placed that it 5 is adapted to be engaged by flaring jaws 40 carried on the door actuating device 20, these jaws 40 being secured to a traveling nut 41, this nut in turn sliding inside a case 42 which is fixed to the elevator car, and being 10 engaged and driven by a screw threaded shaft 43, this shaft turning freely in bearings 44 and 45 secured to the case 42. The shaft 43 is equipped with a brake wheel 46 and is driven through an insulating coupling 47 from a door actuating motor 48.

A solenoid brake is provided as shown in Fig. 6, this brake consisting of a solenoid 49 having a core 50, this core being pivoted on a pin 51 carried on a lever 52, the lever 52 being 20 carried on a pin 53 fixed in a bearing 54 which is secured to the case 42. A band brake 55 encircles the brake wheel 46, being secured at one end 56 to the pin 53, and being secured at the other end on a pin 57 25 carried on the end of the lever 52. This, and similar arrangements, of the brake are common in the art and no novelty is claimed therefor. The brake is provided so that whenever current flows through the solenoid 49 the core 50 is lifted and the brake is released, the brake being immediately applied whenever current is cut off from the solenoid 49.

Sliding freely in the case 42 is a dash-pot 35 rod 60, this rod being provided with a piston 61 sliding freely in a dash-pot 62 secured to one end of the case 42, this dash-pot being provided with cocks 63 by which the flow of air or other fluid from one end 40 to the other thereof may be regulated. Secured to the rod 60 are adjustable stops 64 and 65, these stops being provided with set screws 66 by which they may be secured to the rod 60 in any portion thereof, the stops 45 64 and 65 extending down into such a position that they are engaged at the end of the travel of the nut 41. Secured on the top of the case 42 is an open limit switch 70, and a closed limit switch 71, these limit 50 switches being duplicates of each other, and consisting of a case 72 in which an insulating slab 73 is mounted. A shaft 74 extends through the side of the case 72 and has an operating arm 75 rigidly mounted thereon. A contact arm 76 is secured to the shaft 74 55 inside the case 72, and a spring 77 tends to hold the arms 75 in the position illustrated in Fig. 2, the nut 41 striking against these arms 75 at either end of its travel and drawing them into the position shown in dotted lines in Fig. 2.

Wires 78, 79, 80 and 81 are secured to suitable terminals on the open limit switch 70, and wires 82, 83, 84 and 85 are secured

to similar terminals on the closed limit 65 switch 71, these wires being so connected to various contacts 86 inside these switches that connections will be made as will hereinafter be described.

The interlock switch 16 consists of a case 70 90 in which an insulating slab 91 is mounted. A shaft 92 projects through the side of the case 90, and carries an actuating lever 93 having a roller 94 in the extreme end thereof. A contact arm 95 is normally held 75 in its depressed condition by means of a spring 96 being thrown in the position shown in the drawing by the cam 17 so that contact is made between the arm 95 and a contact member 97. Wires 98 and 99 are 80 connected to the contact 97 and to the arm 95 respectively. Whenever the switch is closed by the roller 94 striking against the cam 17 the arm 95 strikes against the contact 97, thus completing an electrical connection between the wires 98 and 99.

The main controller 14 may be of any form, and a handle operating in a similar manner to the handle 14 may be used to control either an electric or hydraulic elevator. For the purpose of making the operation plain the application to an electric elevator will be described, the parts of the controller being shown diagrammatically, the various types of controller suited to the purpose being well known at the present time in the art and therefore needing no detailed description.

In the form shown diagrammatically, a pair of pivoted contact arms 100 and 101 are 100 connected at their pivots through wires 102 and 103 with the armature 104 of the elevator driving motor, these arms 100 and 101 being connected through an insulating bar 105 to the operating handle 14. Three contacts are provided, the outer ones being connected to a wire 108 and the center one to a wire 107. By moving the handle 14 to the right the wire 102 is connected to the wire 107 and the wire 103 to the wire 108. A reverse movement of the handle reverses these connections. The wire 108 is connected through a wire 109 with a supply wire 110, the wire 108 also being connected to one side of a shunt field 111 of the main motor of the 115 elevator, the other terminal of the shunt field 111 being connected through a wire 112 with the wire 85. Contacts 113 and 114 are suitably fixed in the stationary portion of the controller 13 in such a position that contact between them is closed by an insulated conductor on the operating handle 14 whenever this handle is in its off position, this occurring whenever the elevator is brought to rest. The contact 113 is connected to the supply wire 110 and the wire 114 is connected to the wire 99 leading to the interlock switch 16, the wire 98 of the interlock

switch extending down and being connected to the wires 79, 81 and 82. The wire 78 is connected to a threshold light 115, this light being so placed that it illuminates the threshold of the car, the other terminal of the light 115 being connected through a wire 116 with a main supply wire 117, the wires 110 and 117 having an electrical potential impressed thereon from any suitable source. The wire 84 is also connected to the wire 117. While I have illustrated and described a motor controlled directly by the main controller 15, it is obvious that relays may be used in the main circuits wherever desired.

The door controller 15 may be of any convenient form, that being shown diagrammatically in the drawings consists of two current carrying arms 120 and 121, pivoted on pins 122 and 123, and connected by a bar 124 of insulating material so that they must move together. A spring tends to hold the controller 15 in position to close the door, and means are provided by which the operator may actuate the controller either by hand or otherwise. These arms are adapted to rest on two of three contacts, these contacts being connected to the wires 80, 84 and 83, respectively. The solenoid 49 is connected in series with an armature 126 of the motor 48 across the pins 122 and 123, the shunt field 127 of the motor 48 being connected across the supply wires 110 and 117. Obviously in some cases a series motor may be used in which case the field 127 is dispensed with and a series field is used, this field being in series with the wire 125. If a compound motor is used both fields will be used.

The method of operation is as follows:

With the nut 41 in its closed position, the nut 41 will have contacted with the operating arm 75 of the closed limit switch 71, drawing it into the dotted position as shown in Fig. 2. The nut in Fig. 2 is shown traveling in the direction of the arrow 150 to close the door at an instant just before the arm 75 of the limit switch 71 is moved over to its dotted position. With the arm in this position, the parts will be in the position shown in the diagram in Fig. 7. In this position there will be no flow of current except through the shunt field 127 of the motor 48. When in this position the flaring jaws 40 will be in engagement with the rubber roller 31. With the parts in this position, if it is desired to open the door, the operator moves the door switch 15 in such a manner as to cause the arm 120 to make contact with the wire 80, and the arm 121 to make contact with the wire 125 and thence with the wires 84 and 117. No current will flow unless the switch 16 is closed, and this switch will never be closed except when the elevator is in the proper position to allow the

cam 17 to close it, this position being that in which the floor of the car 11 is approximately flush with one of the floors of the building. The lever 14 must also be in its central or "off" position. When in this position current will flow through the wire 70 110, through the contact 113, the arm 14, and the contacts 114, through the wire 99, and through the arm 95, contact 97, and the wire 98 to the wire 81, through this wire 81 to the contact arm 76 of the switch 70, and to the wire 80, and from this wire through the arm 120 to the solenoid 49 and to the armature 126 of the door actuating motor 48, current flowing from the armature 126 through the arm 121 to the wire 125, and through the wire 84 to the other terminal wire 117 of the circuit. This will result in the solenoid brake 49 releasing, allowing the armature 126 to turn the shaft 43 in such a direction as to actuate the nut 41 in 85 a direction opposite to the arrow 150 to open the door. The movement of the nut 41 will also move the jaws 40, which are in a position engaging the rubber roller 31, this rubber roller 31 sliding in the direction 90 of the arrow 151, of Fig. 8, the roller 35 sliding in the slot 34, and lifting the latch 36 out of the notch 38 so that the runner 33 is free to slide along the track 32 in the direction of the arrow 151 to open the door. 95 This moves the door lever 18 through the latch bar 29, causing the door to open. The opening of the door is arrested by the nut 41 striking against the stop 64 which actuates the piston 61 through the rod 60, thereby 100 providing a retarding means for the mechanism, so that it will not slam. At the same time the nut 41 strikes against the arm 75 of the limit switch 70, moving the moving contact 76 therein out of the position shown 105 in full lines in the diagram, in Fig. 7, and opening the circuit between the wires 80 and 81, so that the current to the motor is interrupted. Current is shut off in the solenoid 49, and the brake is applied, thereby quickly 110 stopping the door actuating motor 48. At the same time the moving arm 76 of the limit switch 70 closes the circuit between the wires 78 and 79 so that the threshold lights 115 are energized, lighting up the threshold. 115 With the parts in this position it is impossible to apply current to the armature 104 of the elevator driving motor, due to the fact that there is no connection between the wires 84 and 85, this connection having been 120 opened by the spring 87 of the limit switch 71 as soon as the traveling nut 41 has started to move to the left as shown in Fig. 2. It is therefore impossible to start the car with the door open.

Whenever it is desired to close the door, the door switch 15 is thrown into the position shown in full lines in Fig. 7, the mov-

ing contact 76 of the switch 71 being in the position shown in dotted lines, and the moving contact 76 of the switch 70 being also in the position shown in dotted lines. With 5 the parts in this position, current flows through the wires 82 and 83, and through the wires 125, 84 and 117, to supply current to the armature 126 in a reverse direction to that previously explained and to release the 10 brake, so that the motor turns in the reverse direction, moving the nut 41 in the direction shown by the arrow 150 in Fig. 2. As soon as the nut 41 starts in this travel the switch 70 assumes the position shown in full lines 15 in the drawing, thus shutting off the threshold lights, and this travel continues until the switch 71 is actuated and thrown in the position shown in full lines in the diagram, thus interrupting the current to the armature 126 and allowing the solenoid 49 to apply the brake. At the same time the stop 65 is struck and the piston 61 assists in stopping the mechanism without jar.

With the parts in the position shown in 20 full lines in the diagram it is possible to apply current to the armature 104 in either direction, the circuit to the wire 107 being closed through the wire 85, the limit switch 71, the wire 84, and the wire 117, the other 25 side of the circuit being supplied through the wires 110 and 109. The actuation of the controller 13 in either direction will enable the operator to run the elevator either up or down at will.

30 It is, of course, understood that this reverse actuation of the nut 41 just described closes the doors 23 and 24 through the rubber roller 31, the bar 29, the lever 18, and their connected parts, the doors being locked in 35 their closed position by the latch 36 falling into the notch 38 on the track 32. It will thus be seen that the elevator operator is free to operate the elevator in either direction so long as the nut 41 is in the closed 40 position, or in a position to the extreme right as viewed in Fig. 2. It is further evident that the operator is unable to actuate the door operating mechanism 20 whenever the lever 14 is in any other position than the 45 center, inasmuch as the circuit to the motor 48 is broken between the contacts 113 and 114 except when the lever 14 is in the central, or "off" position, and this opening of the 50 circuit prevents current being supplied to the armature 126 of the motor 48. It is further evident that with the arm 14 in its 55 center position the operator can only actuate the mechanism 20 when the interlock switch 16 is closed by the cam 17, as the circuit is open between wires 98 and 99 at all 60 times, the circuit being open at all other times so that no other current can be supplied to the armature 126. In other words the door mechanism 20 can only be energized

when the car is approximately level with the 65 floor.

It will further be evident that as soon as the door actuating mechanism 20 is moved from the closed position that it is impossible to actuate the car through the controller 13, 70 due to the fact that the main circuit of the motor is opened between the wires 84 and 85.

It is further evident that these different methods of interlocking are necessary to the safety of the passengers, and to prevent dis- 75 arrangement of the apparatus, due to faulty operation thereof.

I claim as my invention:—

1. In a door actuating device, a sliding nut, means on said nut for engaging the door 80 to be actuated, a screw for driving said nut, a door actuating motor for driving said screw, a dash-pot rod arranged in parallel relation to said screw, a dash-pot, a double acting piston in said dash-pot secured to said 85 rod, and stops on said rod for engaging said nut at either limit of its travel.

2. In a door actuating device, a sliding nut, means on said nut for engaging the door 90 to be actuated, a screw for driving said nut, a door actuating motor for driving said screw, means whereby said nut interrupts the 95 circuit of said motor at either end of said nut's travel, a solenoid brake on said screw, means by which said brake is applied whenever the circuit to said motor is interrupted, a dash-pot rod arranged in parallel relation to said screw, a dash-pot, a double acting piston in said dash-pot secured to said rod, and stops on said rod for engaging said nut at 100 either limit of its travel.

3. In an elevator, a driving motor, a car, means by which said motor drives said car, a main controller, a door on each floor, door actuating means carried on said car, means 105 carried by said door actuating means for opening and closing said doors, a series of interlock cams secured to the walls of the elevator shaft in which said car travels, an interlock switch carried by said car and so 110 placed as to be closed by said interlock cams, means by which said door actuating means is inoperative at all times except when said interlock switch is closed, a main controller by which said driving motor is controlled, 115 and means in said main controller for preventing the operation of said door actuating device except when said controller is in a position to open the circuit to said driving motor.

4. In an elevator, a driving motor, a car, means by which said motor drives said car, a main controller, a door on each floor, door actuating means carried on said car, means 120 carried by said door actuating means for opening and closing said doors, a series of interlock cams secured to the walls of the elevator shaft in which said car travels, an

interlock switch carried by said car and so placed as to be closed by said interlock cams, means by which said door actuating means is inoperative at all times except when said 6 interlock switch is closed, an interlock switch in the circuit of said driving motor, means for opening said switch whenever the door is open, a main controller by which said driving motor is controlled, and means in said

main controller for preventing the operation 10 of said door actuating device, except when said controller is in a position to open the circuit to said driving motor.

In testimony whereof, I have hereunto set my hand at Los Angeles, California, this 18 21st day of March, 1916.

LUTHER E. GROAT.
